ATTORNEY

UNITED STATES PATENT OFFICE.

ERNEST E. HOWARD, OF KANSAS CITY, MISSOURI.

TRAFFIC GATE.

Application filed March 20, 1926. Serial No. 96,351.

My invention relates to a traffic gate and more particularly to one for use on roadways leading to movable bridges or railroad crossings, or at any other location where it is desired to interrupt traffic by barrier, the principal object of the invention being to effect opening and closing movement of the gate by motive power under control of an operator who may be stationed at a distance from the gate.

In accomplishing this and other objects of the invention I have provided improved details of structure, the preferred forms of which are illustrated in the accompanying drawings, wherein—

Fig. 1 is a perspective view of a gate embodying my improvements, illustrating its use on a bridge or viaduct.

Fig. 2 is a horizontal section on the line 2—2, Fig. 1.

Fig. 3 is an enlarged, detail perspective view of the socket members of the gate mounting in spaced relation.

Fig. 4 is a detail view of a double gate, illustrating an arrangement whereby the members at the oncoming sides of the roadway are locked by the members at the off-going sides to stop the oncoming traffic while the other gates are free to move to release the off-going traffic.

Fig. 5 is a vertical section of the gate mounting, a part of the post being broken away for better illustration.

Fig. 6 is a longitudinal, vertical section of the free end of a gate, particularly illustrating the motor drive mechanism.

Fig. 7 is a vertical section on the line 7—7.

Referring more in detail to the drawings, 1 designates a roadway and 2 a sidewalk constituting portions of a bridge or viaduct or of an approach thereto, or to a railroad crossing or other intersection to the roadway.

Mounted at one side of the roadway, preferably on the sidewalk 2, is a post 3, preferably tubular and having a plug 4 at the top, comprising a spherical bearing boss 5 terminating slightly below the top line of the gate.

The gate itself is preferably composed of structural steel to provide a strong, sightly structure, comprising top and bottom rails 6 and 7 of a length sufficient to constitute roadway and sidewalk sections; the post 3 separating the roadway and sidewalk sec-

tions, and having its upper portion housed within the box walls 8—9; the spherical boss at the top of the post seating within the concaved recess 10 in the bottom of a bar 11 fixed to the top rail 6 between the box walls, 60 to pivotally support the gate in conjunction with the ground bearing presently described.

The bottom rail is provided with an elliptical slot 12 through which the bearing 65 post projects, so that the gate may have a limited tipping movement on its universal bearing.

Transverse plates 13, 14, forming part of the post 15 at the free end of the roadway 70 section, extend below the bottom rail, and are provided with bearing apertures 16, and fixed to the outer face of said plates, by rivets or the like 17, are bearing members 18.

Extending through the plate apertures and 75 journaled in the bearings 18 is a shaft 19, held against longitudinal displacement by washers 20 and having fixed thereto, between the plates, a ground wheel 21 having a rough, ground-gripping tread. Rigidly connected 80 with or formed integrally with the ground wheel is a pinion 22, constantly meshing with an annular gear 23 fixed on a shaft 24, journaled in bearings 25 attached to the inner faces of the plates 13, 14, constituting 85 portions of the post 15. The shaft 24 extends into a gear reduction housing 26, where it is connected by any suitable gear reduction mechanism, not shown but indicated by the housing 26, with a shaft 27 90 coupled at 28 with the shaft 29 of a motor 30, provided with an automatic brake 31 adapted for stopping the motor at each limit of travel of the gate.

The motor and gear reduction mechanisms, 95 with their connecting parts, are preferably located on the bottom gate rail 7 adjacent the post 15, but, obviously specific location of these parts is immaterial.

The post 15 comprises, in addition to the transverse plates 13 and 14, the longitudinal plates 32, which extend to about the level of the top line of the ground wheel 21 to house the mechanism as nearly as possible without interfering with movement of the 100 ground wheel.

The motor 30, if of an electrical type, may receive its current through the wire 33 extending through a cable 34 along the bottom rail to the bearing post, out through a con- 110

duit 35 on said post and within a conduit (not shown) to the operator's position, which may be located at some distance from the gate, or at any convenient point.

- 5 I also preferably provide the gate with an audible alarm, preferably consisting of a bell 36 on the gate post, operable by a suitable vibrating mechanism, in circuit with the motor 30, or otherwise operable, so that 10 when the gate is to be closed the alarm will sound and continue sounding until the gate has returned to normal position. The gate may also be provided with suitable warning lights 37. I also provide the socket mounting with an oil cup 38, having a nozzle 39 mounted in a channel 40 in the bearing plate 11 to lubricate the socket bearing.

In order that the gate may lie parallel with the roadway when open, I preferably 20 provide the sidewalk with a pocket 41 so located and proportioned as to receive the ground wheel 21; a post 42 rising from the edge of the pocket to protect the end of the gate when the gate is open, and a post 43 25 rising from the sidewalk to protect that end of the gate under similar conditions. I also provide the railing 44 with a shouldered recess 45 for receiving the end of the sidewalk portion of the gate to form a stop for 30 limiting outward swing of the gate, and with a block 46 for engagement by a switch 47 for stopping the motor as the gate assumes its closed position.

For narrow roadways one gate is sufficient, but for wider roadways, or in any location where such construction is desirable, I divide the gate into two sections, each a duplicate of the other, so that they may swing independently but simultaneously to open 35 and close the roadway. I have shown in the drawings a sectional gate of this kind, one of the sections appearing in its entirety, with its mounting and operating mechanism, the other section being merely indicated by 40 a portion of the free end of the roadway section.

Experience has taught that in the use of 50 barriers of this general character, traffic approaches as near as possible to the gate before stopping; consequently it is practically a necessity to mount the gate for opening with the traffic. With a double gate the same rule may apply for offgoing traffic. As gates of this kind are usually located at 55 some distance from the railroad crossing, or from the movable bridge span, offgoing traffic may be trapped by the gate. It is desirable that this trapped traffic be relieved without permitting oncoming traffic to pass; consequently when two gate sections are 60 employed I arrange them at an angle as shown in Fig. 4, so that the offgoing traffic section may swing outwardly to relieve the offgoing traffic, but movement in the opposite direction causing the ends of the sections to

bind against each other and lock, thereby barring oncoming traffic.

Operation of a gate constructed and assembled as described is obvious. The spherical mounting permits turning movement on a vertical axis, and vertical movement to compensate for any unevenness of the roadway and the difference in elevation due to the arch of the road.

By arranging the motor as described, the power is applied directly to the ground wheel, so that when the motor is active the wheel is revolved to carry the gate forward or back under control of the operator at his station, semi-automatic control being provided for stopping the gate at the proper points.

It is apparent that when the divided, semi-interlocking gate is employed, oncoming traffic may be interrupted while the offgoing traffic is permitted to flow.

What I claim and desire to secure by Letters Patent is:—

1. A traffic gate comprising a pivotally mounted barrier, having a ground wheel at its free end and a motor operatively connected with the ground wheel to rotate the same.

2. A traffic gate comprising a barrier mounted to swing about a substantially vertical axis near one end thereof, a ground wheel near the other end thereof and a motor operatively connected with the ground wheel to rotate the same.

3. A traffic gate comprising a pivotally mounted barrier, having a ground wheel at its free end and a motor operatively connected with the ground wheel to rotate the same, said ground wheel having a gripping surface.

4. A traffic gate comprising a barrier having pivotal mounting at one of its ends, a ground wheel supporting the opposite end of the barrier, a gear wheel carried by the ground wheel, a drive pinion in mesh with the gear wheel and means carried by the gate for operating the pinion.

5. A traffic gate comprising a barrier having pivotal mounting at one end, a ground wheel for supporting the other end of the barrier, a gear carried by the ground wheel, a drive shaft rotatably mounted above the ground wheel, a pinion on the shaft in mesh with the gear wheel, and a motor operably connected to the drive shaft.

6. A traffic gate comprising paired barriers pivotally mounted at opposite sides of a roadway in a line perpendicular to the roadway, the combined length of the barriers being greater than the width of the roadway, whereby the ends of the barriers must contact as they approach said perpendicular line to lock the barriers against continued movement in the direction of said line, supporting ground wheels on said barriers, and an individual motor on each barrier opera-

tively connected with the corresponding ground wheel.

7. In a traffic gate, a barrier comprising upper and lower rails, the lower rail having an elliptical slot with a long axis in the direction of length of the barrier, the upper rail having a downwardly facing socket, a post extended through the opening in said lower rail and having a spherical member on 10 its upper end seating in said socket to pivotally mount the barrier.

8. In a traffic gate, a barrier comprising upper and lower rails, the lower rail having an elliptical slot having its long axis in the direction of length of the barrier, a block attached to the upper rail and having a downwardly facing socket, a post extended through the slot and having a spherical member seating within the socket of the 20 upper rail to pivotally support the barrier, said block having a central aperture and a horizontal cup having a nozzle seated in

said aperture to automatically lubricate the mounting.

9. In combination with a roadway and 25 sidewalk, a barrier pivotally mounted adjacent the sidewalk and having a ground wheel at its roadway end movable over the roadway, the sidewalk having a recess for receiving the ground wheel to align the barrier 30 with the sidewalk, and a post rising from the sidewalk adjacent the said recess for the purpose set forth.

10. In combination with a roadway, a 35 sidewalk and a rail for the sidewalk, the rail having a vertical shouldered recess and a switch shifting surface within the recess, a pivotally mounted barrier having roadway and sidewalk sections, the end of the sidewalk section movable into and from the rail- 40 ing recess, and a motor for operating the barrier.

In testimony whereof I affix my signature.
ERNEST E. HOWARD.
